UNITED STATES PATENT OFFICE.

NILS FREDERICK AMBURSEN, OF NEWTON, MASSACHUSETTS, ASSIGNOR TO THE UNI-FORM COMPANY, OF BOSTON, MASSACHUSETTS, A CORPORATION OF MASSACHUSETTS.

APPARATUS FOR CONSTRUCTING CONCRETE FLOORS.

1,278,087.

Specification of Letters Patent. Patented Sept. 10, 1918.

Application filed September 13, 1917. Serial No. 191,137.

To all whom it may concern:

Be it known that I, NILS F. AMBURSEN, a citizen of the United States, and resident of Newton, in the county of Middlesex and 5 State of Massachusetts, have invented a new and useful Improvement in Apparatus for Constructing Concrete Floors, of which the following is a specification.

The object of the present invention, which 10 is an improvement on the apparatus for constructing concrete floors described in my United States Letters Patent No. 1,216,644, issued February 20, 1917, is to provide means for molding a floor and its supporting beams whereby the depth of the beam boxes may be varied at will.

My invention may best be understood by having reference to several illustrative embodiments of the same shown in the accompanying drawings wherein:—

Figure 1 is a transverse section of one embodiment of my invention. Fig. 2 is a longitudinal section taken on the line 2—2 of Fig. 1. Fig. 3 is a longitudinal section of 25 a modification. Fig. 4 is a plan view of another modification. Fig. 5 is a transverse section taken on the line 5—5 of Fig. 4. Fig. 6 is a transverse section taken on the line 6—6 of Fig. 4.

30 In the particular drawings selected for more fully disclosing my invention, 1, represents the channel irons such as described in my Letters Patent above mentioned, which are suitably spaced and supported by 35 false work (not shown) in the manner described in said patent with their flanges 2, 2 extending upwardly. Spanning the space between each pair of adjacent channels are concrete molds herein shown as metallic arch 40 plates 3, 3, the lower edges of each of which rest on the webs of the channels against the inner faces of the flanges.

As described in said patent, the concrete is poured in the mold so constructed to form 45 the floor and the beam or joist, the sides of a pair of adjacent arch plates and the web of the coöperating channel constituting the beam box. It is usual to employ four sizes of arch plates which are 6 inches, eight 50 inches, 10 inches and 12 inches in height, respectively. However, by providing means for varying the depth of a beam box it is possible to mold beams of the desired thickness by the use of only two sizes of arch

plate, for example: plates 8 inches and 12 55 inches in height. By means of the arch plates which are 8 inches in height beams may be molded which are 6 inches thick, as well as beams which are 8 inches thick, if a device in the nature of a false bottom is employed and, in like manner, by means of arch plates 12 inches in height beams 60 10 inches thick as well as beams 12 inches thick may be molded.

Several arrangements may be employed 65 for varying the depth of the beam boxes, each arrangement comprising a member extending throughout the length of each channel or concrete-form support-member and having its edges resting against the sides of 70 two adjacent arch plates or concrete-forms, the upper surface of each said member being located above the base of each support member.

In Fig. 1 and Fig. 2, I have shown blocks 75 4, which may be of wood, placed transversely in the channels and suitably spaced, said blocks supporting metallic plate 5 about 2 inches above the upper surface of the web of the channel. Extending across the beam 80 boxes are a series of rods 6, or other suitable members for supporting the reinforcing rods 7 which, as shown, may be secured in position by the wire loops 8. It will be understood, however, that any suitable 85 means may be employed for spacing the reinforcing rods in the beam boxes, such, for example, as wire "chairs," which are customarily employed for this purpose.

In Fig. 3, 4' represents a filler block about 90 2 inches in thickness which rests on the web of the channel and extends throughout the length thereof.

It will be obvious that by either of the means above described the depth of a beam 95 box will be reduced and that, for example, a beam 6 inches thick may thereby be molded in a box 8 inches deep, or a beam 10 inches thick in a box 12 inches deep, etc.

It is not necessary, however, to employ 100 the blocks 4 or filler blocks 4' above described, for, as shown in Figs. 4, 5 and 6 a plate, 5', which in this instance preferably is provided with flanges 9 conforming to the slant of the arch plates, is supported by the 105 thimbles 10 surrounding the bolts 11 which project upwardly through the webs of the channels at suitable intervals. Each plate

5' is clamped against its supporting thimbles by means of the nuts 12 threaded to said bolts.

As described in my Letters Patent aforesaid, it is desirable to clamp the lower edges of the arch plates against the flanges 2 and for this purpose the clamp members 13 arranged transversely in the channels at suitable intervals may be employed, the bolts 10 14 passing upwardly through the webs, and the clamps and having the nuts 15 threaded thereto whereby said clamps are secured in position.

It will be obvious that various other means 15 may be employed for varying the depth of the beam boxes and, therefore, I do not limit myself to the arrangements which I have specifically described.

Having thus described illustrative embodiments of my invention, without, however, limiting the same thereto, what I claim and desire to secure by Letters Patent is,—

1. Apparatus for constructing concrete floors comprising in combination laterally-spaced concrete-form support-members, concrete forms supported by and spanning the space between each pair of support members, and a member extending throughout the length of each support member and having its edges resting against the sides of two adjacent concrete-forms, the upper surface of each said member being located above the base of each support member.

2. Apparatus for constructing concrete floors comprising in combination spaced channels, metallic arch plates supported by and spanning the space between each pair of channels with the sides thereof inside the flanges of the channels, and a member 35 extending throughout the length of each channel and having its edges resting against

the sides of two adjacent arch plates, the upper surface of each said member being located above the web of a channel.

3. Apparatus for constructing concrete floors comprising in combination spaced channels, metallic arch plates supported by and spanning the space between each pair of channels with the sides thereof inside the flanges of the channels, and a plate extending throughout the length of each channel and having its edges resting against the sides of two adjacent arch plates, the upper surface of each said plate being located above the web of a channel.

4. Apparatus for constructing concrete floors comprising in combination laterally-spaced concrete-form support-members, concrete forms supported by and spanning the space between each pair of support members, a plate extending throughout the length of each support member and having its edges resting against the sides of two adjacent concrete forms and means for holding each said plate above the base of a support member.

5. Apparatus for constructing concrete floors comprising in combination spaced channels, metallic arch plates supported by and spanning the space between each pair of channels with the sides thereof inside the flanges of the channels, a plate extending throughout the length of each channel and having its edges resting against the sides of two adjacent arch plates, bolts extending upwardly through the webs of each channel, and means cooperating with each bolt for supporting said plates above the webs of said channels, respectively.

In testimony whereof I have hereunto subscribed my name.

NILS FREDERICK AMBURSEN.
